[57] **CLAIM**

The ornamental design for siding panel, as shown and described.

DESCRIPTION

FIG. 1 is a fragmentary perspective view of a siding panel of the present invention. The siding panel is broken on the end to disclose indefinite length;

FIG. 2 is an enlarged broken end elevational view thereof; FIG. 3 is an enlarged fragmentary perspective view thereof; and,

FIG. 4 is an enlarged fragmentary rear elevational view thereof.

The broken lines illustrations in the drawing are for illustrative purposes only, and form no part of the claimed design.
